SELF-SEALING ONE-WAY DRAIN VALVE

James B. Clark, Jr., Monkton, Michael M. Behles, Baltimore, and Donald K. Mackenzie, Jr., Middle River, Md., assignors to The Martin Company, a corporation of Maryland

Application November 3, 1955, Serial No. 544,735

3 Claims. (Cl. 114—185)

The present invention relates to a one-way drain valve and more particularly to a valve of this type which is uniquely designed for use in conjunction with marine vessels and flying boats.

It is known that marine vessels including flying boats will take on water to an extent depending upon many factors among which could be mentioned the hull construction, openings in the vessel or boat and their height above the water level, the condition of the water, turbulent or quiet, the speed of the vessel if moving, etc. Since the water taken on by the vessel or boat will increase its over-all weight and thus affect its performance by decreasing its efficiency, it will be appreciated that any means which can be provided to remove this water before it has a chance to collect in appreciable quantities, which at the same time does not materially increase the weight of the vessel or boat, would be a valuable asset. Further, the water can be a source of annoyance and discomfort even when taken on in small quantities and hence from a purely subjective standpoint, rapid and efficient removal of water taken on would be extremely desirable.

Accordingly, it is an object of the present invention to provide such a means for removing water from vessels or flying boats which means is in the form of a self-sealing, one-way drain valve which can be conveniently located in any part of a vessel or boat to allow water that has collected in this part to drain overboard and at the same time to prevent outside water, such as sea water, from entering the vessel or boat through the valve. As will be appreciated, this will neatly solve the problem of removing water which tends to collect in at least this part of the vessel or boat. The weight of the device is negligible and to all intents and purposes does not add to the weight of the vessel or boat. Thus, the vessel or boat in which the present invention is installed will not have its operational characteristics altered or its efficiency decreased.

It is a further object of the present invention to provide a self-sealing, one-way drain valve which is composed of a minimum of parts only one of which moves and which is characterized by a very simple and light weight construction whereby it will not to any finite degree increase the weight of the vessel or boat in which it is incorporated.

It is a further object of the present invention to provide a self-sealing, one-way drain valve of durable construction for mounting in a boat which will function efficiently and economically to prevent water or other fluid from passing inboard through the valve and at the same time will expediently allow water or other fluid collected in the boat to drain overboard.

Other objects and advantages of the present invention will become more fully apparent from the following detailed description when taken in conjunction with the drawings in which:

Figure 1 is a view in section showing the mounting of the valve of the present invention in a flying boat;

2

Figure 2 is a view in section taken along line 2—2 of Figure 1; and

Figure 3 is a view in section taken along line 3—3 of Figure 1.

- 5 Referring now to the drawings, there will be described a preferred embodiment of the present invention. In the drawings, 10 represents the anchor floor of a flying boat. Attached to the floor 10 is a sump 11 with its mouth or upper end in registry with a suitable hole defined in the floor 10. Fixed in the sump 11 is a perforated plate or screen 12 shown best in Figure 3. Attached to the bottom of the sump 11 is the self-sealing, one-way drain valve of the present invention. The valve consists of a main body 13 which is cylindrical in form, and preferably transparent in order to afford visual inspection to determine when cleaning is necessary, end plates 14 and 15 each of which engage with the body 13 through the intermediary of suitable sealing gaskets 16 and 17. These gaskets may be composed of synthetic rubber and serve to seal the body of the valve as well as other functions which will become apparent as the description progresses. The end plates 14 and 15 are annular in character defining central holes and projecting lugs 21. Bolt and nut assemblies 22 connect the end plates, gaskets and body together. The associated gaskets 16 and 17 are likewise annular in character and define central holes which are concentrically aligned with the holes in the end plates. Positioned axially in the body 13 of the drain valve are a series of guide vanes 18. Four such vanes 18 are shown. A ball valve 19 is located within the body 13 and is constrained by the axially mounted vanes 18 for axial movement within the body 13. A suitable discharge tube 20 is attached to end plate 15. A flexible tube 23 is connected to discharge tube 20 at one end and to an outlet pipe 24 fixed in the hull 25 of the flying boat at its other end. The ball 19 is preferably hollow in character and relatively light. For this purpose, a table tennis ball prepared to preselected standards can be used.
- 20 As will be evident from the drawing, there exists an internal air pressure in the vessel which exerts a force in the direction indicated by the arrow.
- 25 The operation of the self-sealing, one-way drain valve is as follows. The ball 19 is normally held in its lowermost position whereat it is seated on the gasket 17. The ball is held in this position by the indicated air pressure. Any water that collects on the anchor floor 10 runs through the hole defined by the anchor floor 10 through the screen 12 and into the sump 11. Since the holes defined by the end plate 14 and gasket 10 are unobstructed, the water will fall into the body 13 of the valve and will float the ball 19. As soon as the ball 19 rises from its seat on the seal or gasket 17, the water will begin to run out of the discharge tube 20 to the exterior of the flying boat. If water should enter the valve body 13 in appreciable quantities, the ball 19 will be floated to a position at the top of the valve body where it will seat on seal or gasket 16 thus sealing off further inflow of water and at the same time will allow water already in the body 13 to drain off through the discharge tube 20. As will be evident, any back wash through the discharge tube 20 from the outside will immediately float the ball 19 and seat it on the seal 16 thus preventing water from entering the ship from the outside. As previously explained, the ball 19 is constrained only for axial movement within the valve body 13 by virtue of the presence of the axial extending guide vanes 18. These vanes restrain the ball and facilitate its seating on the gaskets or seals 16 and 17.
- 30 Whereas independent axial guide vanes 18 have been disclosed, it will be appreciated that any means can be employed which will constrain the movement of the ball

19 axially. Thus, for example, the guide vanes 18 may be replaced by a perforated retainer tube composed of any material or even a spring. Also, the bolts 22 can extend within the cylinder 13 and in effect function additionally as the means to constrain the ball 19. The only consideration insofar as selecting a suitable means is to be sure that a favorable available water volume versus volume displacement of the ball ratio is preserved to insure that the ball will be floated. Thus, the vanes or other means cannot take up too much volume.

Although the present invention has been shown and described with reference to a preferred embodiment, nevertheless, various changes and modifications which are obvious to one skilled in this art from a knowledge of the present invention are deemed to be within the spirit, scope and contemplation of the present invention.

What is claimed is:

1. A self-sealing one-way drain valve system for draining the bilge of a marine vessel comprising a valve housing located in the bilge of the vessel, the upper end of said housing being connected in operative relation to a sump, a discharge tube connected to the lower end of said valve housing and leading to a point outside the hull of the vessel, said valve housing being vertically disposed and having a passage therethrough for the flow of water from said sump to a point outside said hull, vertically aligned upper and lower valve seats at the upper and lower ends, respectively, of said valve body, a light weight ball valve located in said valve housing and freely movable between said valve seats, resilient means for assuring complete circumferential contact between said ball valve and said valve seats, and guide vanes located in-

ternally of said valve housing to guide the movements of said ball valve, said ball valve being normally biased into contact with said lower valve seat by internal pressure, and being substantially lighter than the fluid passing through said valve body, being caused to float in said valve body to permit fluid to pass in the downward direction through said valve body, said ball valve, when caused to float upwardly into seating contact with said upper valve seat, being effective to prevent the reverse flow of fluid through said valve body.

2. The self-sealing one-way drain valve as defined in claim 1 in which said valve housing is transparent so as to permit visual inspection for determining if cleaning is necessary.

3. The self-sealing one-way drain valve as defined in claim 1 in which said valve housing comprises a generally cylindrical main body, and an end plate secured at each end thereof, said end plates being secured by a plurality of generally vertically disposed bolts holding said end plates in sealed relation with respect to the ends of said main body, whereby said valve housing can be easily disassembled for servicing by loosening said bolts.
